DESIGN FOR A LAMP SHADE

William H. Biever, Philadelphia, Pa.

Application April 4, 1938, Serial No. 76,266

Term of patent 3½ years

To all whom it may concern:

Be it known that I, William H. Biever, a citizen of the United States, residing at Philadelphia, in the county of Philadelphia and State of Pennsylvania, have invented a new, original, and ornamental Design for a Lamp Shade, of which the following is a specification, reference being had to the accompanying drawing, forming part thereof.

I claim:

The ornamental design for a lamp shade, substantially as shown.

WILLIAM H. BIEVER.
